A. E. RHOADES,
 FILLING EXHAUSTION INDICATING MECHANISM FOR LOOMS,
 APPLICATION FILED DEC. 19, 1911.
1,024,023. Patented Apr. 23, 1912.

UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

FILLING-EXHAUSTION-INDICATING MECHANISM FOR LOOMS.

1,024,023.

Specification of Letters Patent. Patented Apr. 23, 1912.

Application filed December 19, 1911. Serial No. 666,737.

To all whom it may concern:

Be it known that I, ALONZO E. RHOADES, a citizen of the United States, and resident of Hopedale, county of Worcester, State of Massachusetts, have invented an Improvement in Filling-Exhaustion-Indicating Mechanism for Looms, of which the following description, in connection with the accompanying drawing, is a specification, like characters on the drawing representing like parts.

This invention relates to looms provided with mechanism to effect automatically a change in the operation of the loom when the filling in the active or working shuttle is substantially exhausted, that is, before such filling runs out completely.

The change in the operation of the loom may be the stoppage thereof, or it may be, 20 and more frequently is, the replenishment of the working filling. Looms of this type are usually termed "feeler" looms because a member of the controlling mechanism is arranged to coöperate with or feel intermittently the filling in the working shuttle and when substantial exhaustion thereof is detected by such member, or feeler, the desired change in loom operation is brought about.

30 Ordinarily the feeler is arranged to coöperate with the filling in the shuttle on every other pick, many forms of feeler mechanisms having been devised, but as a matter of fact the coöperation of the feeler with the filling is unnecessary until a near approach to substantial exhaustion thereof is reached, and with certain kinds of filling the continued action of the feeler in coöperating intermittently therewith is objectionable.

40 It has been proposed to hold the feeler inoperative in a position of rest after filling replenishment has been effected until substantial filling exhaustion is approached, 45 and thereupon the feeler is thrown into operative position. This arrangement is necessarily based upon the quantity of filling on a full bobbin, and the number of picks necessary to weave off the filling down to 50 what may be termed the danger point, hence only full bobbins can be used if the feeler mechanism is designed to replenish filling in the working shuttle, and care must

be taken in the spinning operation to provide the bobbins with a substantially uniform quantity of filling. In the practical operation of filling replenishing looms, however, it is not feasible to restrict the use to full bobbins alone, for commercially bobbins having varying yarn loads must be utilized, and if the device above mentioned is set for full bobbins it is useless with practically filled bobbins, and vice versa. In the first instance the yarn will run out before the feeler is thrown into action, and if the device is set for partially filled bobbins the feeler will be thrown into action too soon if full bobbins are used. Such device, then, is not adapted for commercial use to any extent, as will be manifest.

70 My present invention has for its object the production of filling exhaustion indicating mechanism so constructed and arranged that it is adapted for use commercially irrespective of the quantity of filling on the filling-carrier or bobbin in the working shuttle, such mechanism being thrown into and out of action alternately with respect to the filling in the active or working shuttle.

To reduce as much as possible unnecessary coöperation of the feeler device and the filling the periods of inactivity of such device are relatively long and the periods of its activity relatively short until the danger point is reached, whereupon the 80 feeler device coöperates with the filling on alternate picks until substantial exhaustion of the filling is detected.

The means whereby the feeler device is held inactive with respect to the filling is rendered inoperative automatically at regularly recurring intervals, and the released feeler device is at once restored to the control of such means by the action of a moving part of the loom, by or through the 90 filling in the shuttle, until the filling has woven off to such an extent that it is incapable of thus putting out of action the feeler device. That is the danger point, and thereafter the feeler device operates in a familiar 95 manner until it performs its ultimate function upon detection of the substantial exhaustion of the filling.

100 Any suitable feeler mechanism can be used in carrying out my invention and herein I have chosen to illustrate my in-

vention in connection with filling exhaustion indicating mechanism substantially such as is shown in United States Patent No. 789,471 granted May 9, 1905 to Wood and Northrop.

The various novel features of my invention will be fully described in the subjoined specification and particularly pointed out in the following claims.

10 Figure 1 is a top plan view of the filling exhaustion indicating mechanism of an automatic loom of the type shown in the patent referred to, with one practical form of my present invention embodied therein, only 15 so much of the loom structure being shown as is necessary to a proper understanding of the invention. Fig. 2 is an enlarged left hand side elevation of a portion of the mechanism illustrated in Fig. 1, to show more 20 clearly the means whereby the feeler device is alternately held out of operation and released; Fig. 3 is a detail of a portion of the releasing means, to be referred to; Fig. 4 is 25 an enlarged detail in side elevation and partial section, of the feeler proper, and the device for holding it inactive with respect to the filling, but with the feeler released; Fig. 30 5 is a view similar to Fig. 4, but in this instance the holding device is in operative position maintaining the feeler at rest and inoperative.

Referring to Fig. 1 the lay A having at the feeling end thereof a shuttle-box B, the shuttle C of a well known automatically self-threading type, (both the side wall of the shuttle and the front box wall being apertured for the entrance of the feeler into the shuttle) the breast-beam having the usual notched holding-plate D for the shipper, 40 and the controlling rod or shaft E whereby the filling-replenishing mechanism is called into operation to change the filling in the working or active shuttle, may be and are all of well known construction, the shaft E 45 being the only member of the replenishing mechanism necessary to illustrate. In practice such mechanism may be of the type shown in United States Patent No. 529,940 granted November 27, 1894 to Northrop, 50 and herein the replenishment of the working shuttle with a fresh supply of filling is the change in the operation of the loom which is brought about when substantial exhaustion of the filling in such shuttle is detected.

55 The filling exhaustion indicating mechanism herein illustrated comprises a feeler F yieldingly mounted to slide back and forth in a suitable stand G mounted on the holding plate D, the shank H of the feeler 60 being prolonged and projecting beyond the front end of the stand, a usual projecting spring I, Fig. 4, being arranged to move the feeler rearward, said feeler having pivotally mounted upon it an actuating member J provided with an adjustable bunter K,

said actuating member being adapted to at times engage and swing forward the outer end of the pivoted controller L, all as in the Wood and Northrop patent referred to. Such forward movement of the controller 70 acts through the bent end M of a transmitter N to rock the latter on its fulcrum O, and thereby the link P connected with the controlling shaft E is placed in position to be engaged by a vibrating member Q, in practice the weft-hammer, to turn the said shaft and thereby bring about filling replenishment when the shuttle is boxed at the replenishing side of the loom, all as provided for in the Wood and Northrop patent. In 80 such patented structure the feeler F enters the shuttle and impinges against the filling therein each time the shuttle is in the box B, and as the lay beats up the feeler and the member J thereon are moved forward as a 85 unit, the said member J clearing the controller L so long as there is a substantial amount of filling present. When, however, the filling weaves off to the point of substantial exhaustion the feeler is permitted to enter the shuttle so far that the bunter K will impinge upon the shuttle wall, and thereby the member J is rocked, bringing its front 90 end into engagement with the controller L and swinging the latter operatively as the 95 lay beats up. Thereupon the transmitter N is rocked and the vibrator Q engages and moves forward the link P to turn the rock-shaft E, and filling replenishment is effected. It will thus be obvious that the 100 feeler impinges upon or coöperates with the filling in the shuttle on every alternate pick from the time a bobbin is inserted in the shuttle until the filling is substantially exhausted, and this is the ordinary operation 105 of filling exhaustion indicating mechanisms. It will also be obvious that such intermittent coöperation of the feeler with the filling is wholly unnecessary, so far as concerns the ultimate function of the feeler mechanism, 110 for the greater part of the time during which the filling is weaving off from the bobbin. When using fine, soft or delicate filling this continual coöperation of the feeler therewith is often objectionable, tending to break, cut or otherwise injure the filling.

By my present invention I obviate the unnecessary action of the feeler with respect to the filling by maintaining the feeler inoperative with respect to the filling for relatively long periods, and permitting the feeler to act for intervening short periods until the filling is woven off to what I may term the danger point, that is, when the filling has been woven off to nearly the point of substantial exhaustion. When such danger point is reached the feeler remains operative with respect to the filling and coöperates therewith on alternate picks until substan- 115 120 125 130

tial exhaustion is detected, and thereupon the exhaustion indicating mechanism performs its ultimate function.

I use the term "substantial exhaustion" 5 in the sense commonly accepted, meaning thereby that when the ultimate function of the exhaustion indicating mechanism is performed there will still remain a small portion of filling on the filling-carrier or bobbin in the shuttle.

In the present embodiment of my invention I cut away or notch the feeler shank H to leave a transverse square shoulder 1 at the front end of the notch, and preferably I 15 bevel rearwardly the rear end of the notch, as at 2, and I provide a holding device to at times engage said shoulder and thereby maintain the feeler F in retracted position, Fig. 5. At such time the feeler is inoperative and inactive with respect to the filling in the working shuttle. That is, it will not coöperate with the filling on alternate picks, the relative positions of the shoulder 1 and the holding device being properly arranged 20 for that purpose. Herein said device is shown as a pawl 3 having a lateral extension or lug 4, the pawl being slotted at 5 to receive a shouldered fulcrum pin 6 clamped thereon by a nut 7. The pin is mounted to rock in 25 a transverse bearing 8 conveniently mounted on or forming part of the usual controller guard R, and at its inner end the pin has fixed upon it by a sleeve 9, Fig. 1, containing a coiled spring 10, one end of the spring being attached to the sleeve and the other end to the bearing 8. The spring is so wound as to press the tip of the pawl 3 downward toward the feeler shank H, over which said pawl extends. Any other suitable means 30 for depressing the pawl may be employed, but the construction shown is simple and convenient, and protects the spring.

By adjustment of the detent or holding pawl, by the slot 5, the device can be readily 45 set for proper operation, and so, too, adjustment is provided for the final release of the feeler prior to substantial exhaustion of the filling. That is, by setting said pawl rearward with respect to its fulcrum pin 6 50 there will be less filling on the bobbin when the "danger point" is reached than will be the case if the pawl is set forward with respect to its fulcrum pin. This adjustment is entirely independent of the adjustment 55 of the bunter K, it will be understood, that latter adjustment determining how much filling will remain on the bobbin when "substantial exhaustion" is detected by the feeler device.

60 From the foregoing description it will be clear that when a fresh supply of filling is inserted in the shuttle the filling will engage the projected feeler on the first feeling pick after replenishment, and as the lay beats up the feeler F will be moved for-

ward, and thereby the shoulder 1 will be carried forward beyond the tip of the pawl 3, so that the latter will drop and engage such shoulder as the lay recedes from front center. Consequently the feeler will be held 70 in its forward position, inoperative and inactive with respect to the filling on subsequent feeling picks as long as the feeler is under the control of the holding device or pawl.

Means for effecting periodic release of the feeler will now be described. The lay has attached to it a depending bracket 11 to which is pivoted at 12 a frontwardly extended link 13 joined at 14 to a depending 80 pawl-carrier 15, clearly shown in Fig. 2. A lateral pin 16 projects outwardly from the pawl-carrier near its upper end and is mounted to rock in a bearing 17 forming part of a bracket 18 fixed on the under 85 side of the holding plate D. As shown in Fig. 1 the bracket extends outward beneath the feeler stand G, said bracket having a frontwardly extended and upturned arm 19 which provides a bearing for a short shaft 20 having attached to its inner end a ratchet 21. Said ratchet rotates in a vertical plane adjacent the feeler stand G, and it is provided with a lateral tripping stud 22 which moves in a circular path which is intersected 90 by the lug 4 on the detent pawl 3. Referring to Figs. 1 and 2 it will be apparent that once in every revolution of the ratchet 21 the tripping stud 22 will move up under and raise the lug 4, thereby lifting the pawl 3 100 into inoperative position above the path of the shoulder 1 on the feeler shank. Said ratchet is advanced step by step by an actuating pawl 23 pivoted on the pawl-carrier 15 at 24, Fig. 3, and held in engagement with 105 the ratchet teeth by a suitable spring 25 connecting the pawl-carrier and the pawl-tail 26. As shown in Figs. 1 and 3 the pawl is mounted on the pawl-carrier at its inner side, to clear the bearing 17.

110 Referring to Fig. 2 it will be seen that the feed pawl 23 is retracted on each forward beat of the lay, and feeds forward the ratchet 21 as the lay swings back, and if the ratchet has, for example, 36 teeth and is advanced one tooth for each pick then once in every 36 picks of the loom the detent or holding pawl 3 will be rendered inoperative so far as concerns the feeler, and the latter is released. The period during which the 120 pawl-lug 4 and tripping pin 22 remain in engagement manifestly measures the time during which the feeler is free to coöperate with the filling in the shuttle on the feeling picks, while the greater portion of the filling 125 is weaving off. Such active periods are very short compared to the inactive periods of the feeler, for two to four picks will usually measure the time during which the tripping pin controls the detent pawl. Let it be sup-

posed that the feeler has detected substantial exhaustion of filling and that in consequence a fresh supply of filling has been inserted in the shuttle. On the first feeling 5 pick the feeler will coöperate with the filling in the shuttle and as the lay beats up the feeler will be moved forward, carrying the shoulder 1 well forward of the tip of the pawl 3, so that as the lay swings back 10 said pawl will drop behind the shoulder and the feeler will be held in its forward position, and on subsequent feeling picks the feeler will be held inoperative and inactive with respect to the filling. By taking 15 advantage of the momentum of the feeler when moved forward on the beat up the pawl 3 can be set so that there will actually be no contact of the feeler and filling subsequently while the feeler is maintained inoperative. Even should this close adjustment be deemed unnecessary it will be manifest that there will be in the beginning but the lightest contact between the feeler and the filling, for the latter weaves off rapidly 20 and thereby steadily reduces the diameter of the yarn mass opposite the feeler. When the feeler has thus been rendered inactive by the movement of the lay, acting through the filling in the shuttle, said feeler is maintained at rest and inactive until the revolution 25 of the ratchet 21 causes feeler release through coöperation of the tripping pin 22 and the pawl lug 4. Upon such feeler release the feeler is permitted to coöperate with the filling for one or two feeling picks, and each time the feeler is moved forward far enough for the pawl 3 to coöperate with the shoulder, but such coöperation is not effected until the pawl is released by the 30 tripping pin. This periodical release of the feeler from the detent pawl and the following return of the feeler to the control of said pawl continues until the filling is woven off to such an extent that there is insufficient filling in the shuttle to move the feeler forward far enough to carry the shoulder 1 beyond the tip of the pawl 3. The filling has then been exhausted to the danger point, and thereafter the feeler coöperates intermittently with the filling, that is, 35 on alternate picks, until substantial exhaustion of the filling is detected.

From the foregoing description it will be clearly understood that once for a given 40 number of picks measuring the inactive periods the feeler is released and permitted to coöperate with the filling, and that after each of such releases the feeler is again restored to the control of the means which 45 maintain it inactive and at rest, until the filling has been exhausted to the danger point, and then the feeler operates in usual manner until substantial exhaustion is detected. By this alternation of short periods 50 of activity and relatively long periods of

inactivity the feeler mechanism is adapted to operate properly to detect substantial exhaustion no matter what quantity of filling is on a bobbin when it is inserted in the shuttle. Consequently bobbins which have 55 been more or less denuded of the filling can be used just as well as completely filled bobbins, and this is very important when it is remembered that breakage of filling requires the insertion of a new bobbin in the 60 shuttle, for such ejected bobbins must be used again to weave off the filling remaining thereon.

The rear end 2 of the notch in the feeler shank H is beveled to act as a cam against 65 the tip of pawl 3 when the extreme frontward movement of the feeler is effected, reducing the wear between said parts.

I have shown one practical and simple form of means for maintaining the feeler 70 inoperative, and at rest, and simple means for effecting periodical release of the feeler from the control of the first-named means, but other forms of detaining and releasing means may be used, and a different arrangement of parts may be employed, by those skilled in the art without departing from the spirit and scope of my invention as set forth in the claims hereunto annexed.

The particular form of exhaustion indicating mechanism shown herein is used for purposes of illustration, and does not in any way restrict my invention to use in connection therewith.

Having fully described my invention, 100 what I claim as new and desire to secure by Letters Patent is:

1. In a loom, a feeler adapted to coöperate intermittently with the filling in the active shuttle and to bring about a change 105 in the operation of the loom when substantial exhaustion of such filling is detected, a device to maintain the feeler at rest and prevent coöperation thereof with the filling, and means to render said device inoperative 110 at predetermined intervals and thereby permit coöperation of the feeler and the filling at such times, combined with other means to restore automatically the feeler to the control of such device after each of such times 115 of feeler activity occurring prior to substantial filling exhaustion.

2. In a loom, a yieldingly sustained reciprocating feeler to coöperate with the filling in the active shuttle and to bring about a change 120 in the operation of the loom when substantial exhaustion of such filling is detected, a device to maintain the feeler at rest in retracted, inoperative position, means acting at regularly recurring intervals to render said device inoperative and thereby release the feeler from its control, and means whereby the released feeler is restored to the control of said device by coöperation 125 with the filling on a subsequent beat up 130

until a predetermined diminution of the filling in the shuttle has been reached.

3. In a loom, a yieldingly sustained reciprocating feeler to coöperate with the filling in the active shuttle and to bring about a change in the operation of the loom when substantial exhaustion of such filling is detected, a detent pawl adapted to engage the feeler and hold it inoperative in retracted position, a device acting at regular intervals to trip said pawl and thereby release the feeler, the latter when released coöperating in normal manner with the filling, and means operating automatically after each release of the feeler to restore it to the control of the detent until substantial filling exhaustion is approached.

4. In a loom, a spring-projected, reciprocating feeler adapted to coöperate with the filling in the active shuttle and to bring about a change in the operation of the loom when substantial filling exhaustion is detected, the feeler being retracted by contact with the filling on the beat-up, a detent to engage the feeler and maintain it retracted and inactive with respect to the filling, automatically acting means to trip the detent at regular intervals and thereby effect release of the feeler to coöperate with the filling, and a moving member of the loom acting through such coöperation upon the beat-up to retract the feeler and effect reengagement of the detent therewith until the filling has woven off to a predetermined extent, whereupon the feeler when released will continue to coöperate with the filling until substantial exhaustion thereof is detected.

5. In a loom, a yieldingly sustained feeler adapted to coöperate with the filling in the active shuttle and bring about a change in the operation of the loom upon substantial exhaustion of the filling, an adjustable device to maintain the feeler inactive with respect to the filling, and means to release the feeler from the control of such device at regular intervals and permit coöperation of said feeler and the filling in the shuttle, combined with means acting by and through such coöperation to replace the feeler under the control of said device after each release until the filling has woven off to a predetermined extent but short of substantial exhaustion, adjustment of said device fixing the extent to which the filling shall weave off when it ceases to restore the feeler to the control of such device.

6. In an automatic filling replenishing loom, mechanism, including a feeler adapted to coöperate intermittently with the filling in the active shuttle, to bring about filling replenishment when the feeler detects substantial exhaustion of the filling, a detent to coöperate with the feeler when retracted by coöperation with the filling on the beat up and hold the feeler retracted,

and means operating automatically to render said detent inoperative at regularly recurring intervals, to release the feeler and permit it to coöperate with the filling, combined with means whereby the feeler after each release is restored to the control of the detent by coöperation of the feeler with the filling until the latter has woven off to an extent approaching substantial exhaustion

70

7. In an automatic filling replenishing loom, mechanism, including a feeler adapted to coöperate intermittently with the filling in the active shuttle, to bring about filling replenishment when the feeler detects substantial exhaustion of the filling, said feeler having a shouldered shank, a detent pawl mounted on a stationary part of the loom and adapted to engage the shoulder of the feeler shank when the feeler is retracted, to restrain the feeler from operation, a revolving member having a device thereon to trip the pawl at each revolution of the said member, whereby the feeler is released and permitted to operate normally, and means to effect step by step rotation of said member, combined with means whereby the feeler after each release is restored to the control of the pawl by coöperation with the filling on the beat up until the filling has been diminished to a predetermined extent.

75

8. In a loom, mechanism to detect substantial exhaustion of the filling in the active shuttle and thereupon to bring about a change in the operation of the loom, and means to prevent and permit, alternately, the detecting action of such mechanism, said means comprehending a preventing member rendered inoperative at regularly recurring intervals, and a moving member of the loom acting by or through the filling in the active shuttle to restore said mechanism to the control of the preventing member each time it is rendered inoperative until a predetermined and less than substantial exhaustion of the filling is reached.

80

9. In a loom, mechanism to detect substantial exhaustion of the filling in the working shuttle and thereupon to bring about a change in the operation of the loom, and means to cause said mechanism to have short periods of activity and intervening longer periods of inactivity with respect to the filling prior to substantial exhaustion thereof, said means including an intermittently operating member to control and maintain at rest the mechanism during its longer periods of inactivity, and a moving member of the loom to act through the filling in the shuttle and control said mechanism during its shorter periods of activity and up to the time substantial exhaustion of filling is detected.

85

10. In an automatic filling replenishing loom, in combination, mechanism to detect substantial exhaustion of the filling in the

90

95

100

105

110

115

120

125

130

active shuttle and thereupon to bring about replenishment of filling therein, and means to cause said mechanism to have short periods of activity and intervening longer periods of inactivity with respect to the filling prior to substantial exhaustion thereof, said means including a member to control and maintain at rest such mechanism during the longer periods, a releasing device to render said member inoperative periodically, and a moving member of the loom acting by or through the filling in the active shuttle to restore said mechanism to the control of the restraining member each time the latter is rendered inoperative until a predetermined and less than substantial exhaustion of filling is reached.

11. In a loom, a feeler device, means to hold it at rest out of engagement with any moving part of the loom, mechanism to render said means temporarily inoperative at regular intervals, to thereby release the feeler device and permit it to be engaged by the filling in the shuttle and restored to the control of such means on the beat up, after each release of the feeler device, until the filling in the shuttle approaches substantial exhaustion.

12. In a loom, a feeler adapted when in operative position to engage intermittently the filling in the active shuttle to be moved thereby until such filling is diminished to a predetermined extent, means to engage the feeler and hold it at rest in the position to which it was moved by engagement with the filling, and mechanism acting at regular in-

tervals irrespective of the quantity of filling in the shuttle to render said means inoperative temporarily, to thereby release the feeler and permit operative positioning thereof, combined with a moving member of the loom which causes filling-induced movement of the feeler after each release thereof to restore the feeler to the control of the holding means until a predetermined diminution of the filling has been reached.

13. In a loom provided with an instrumentality to replenish automatically the filling in the working shuttle, and with mechanism to cause the operation of such instrumentality when the filling in the shuttle is substantially exhausted, said mechanism including a member adapted to detect substantial exhaustion of the filling, in combination, means to permit temporary operation of said member to feel the filling at regular intervals prior to substantial exhaustion thereof, and other means to maintain said member inoperative and at rest between such intervals, combined with a device to cause movement of said member into inoperative position by or through coöperation with the filling after each replenishment of the shuttle with filling.

In testimony whereof, I have signed my name to this specification, in the presence of two subscribing witnesses.

ALONZO E. RHOADES.
